(57) CLAIM

The ornamental design for a screenhouse tent pantry, as shown and described.

DESCRIPTION

FIG. 1 is a perspective view showing an ornamental design of a screenhouse tent pantry incorporating the new design; FIG. 2 is a front elevation view thereof;

FIG. 3 is a top plan view thereof; and,

FIG. 4 is a right side elevation view thereof, the left side being a mirror image thereof.

The broken lines are shown for illustrative purposes only and form no part of the claimed design.
